B. J. Craig

ATTORNEY.

UNITED STATES PATENT OFFICE.

ARTHUR E. SMITH, OF LOS ANGELES, CALIFORNIA.

MEDICINAL APPLICATOR.

Application filed June 7, 1926. Serial No. 114,070.

This invention relates to medicinal applicators.

The general object of the invention is to provide an automatic measuring medicinal applicator which is adapted for accurately measuring and introducing medicinal compounds into the vagina for medicinal purposes.

In treating female diseases it is essential to provide an accurate, convenient, sanitary means for introducing the desired drug or compound into the vagina. My invention satisfies these requirements and is particularly useful in treating such diseases as catarrhal inflammations, vaginitis, cervicitis, leucorrhea, gonorrhea, etc.

The more common drugs which may be employed in using my invention are, boro-glycerin; ichthyol-glycerin; guaiacol-glycerin; tannic acid; mercurochrome, and other semi-viscous medicinal compounds.

One embodiment of my invention is shown in the accompanying drawings, wherein:

Fig. 1 is a side elevation of an applicator embodying the features of my invention.

Fig. 2 is a front view of the applicator.

Fig. 3 is a longitudinal central sectional view showing the positions taken when the applicator is being filled.

Fig. 4 is a view similar to Fig. 3, showing the position of parts after the applicator has been operated.

Fig. 5 is an enlarged detail sectional view, and

Fig. 6 is a partial sectional view of the applicator.

Referring to the drawings by reference characters I have shown an applicator embodying the features of my invention as 10.

40 This applicator comprises a hollow body, or receptacle portion 11 having a hollow elongated neck 12 thereon. The body and neck are both preferably cylindrical and the neck has a bulbous member 14 secured at the end 45 thereof. This member is provided with a discharge opening 15.

The end of the body opposite the neck is provided with a threaded closure 16 through which an operating member 17 projects. This 50 member has a piston 18 fixed thereon and also has a rod 19 thereon. The rod 19 is provided with a valve member 20 at its extremity which is adapted to fit in the opening 15 to close this opening.

55 The piston 18 is provided with a sleeve 21 and a closure 21' which in the position shown

in Fig. 3 terminates beyond an aperture 22, which is surrounded by an internally threaded collar 23 arranged externally on the body 11. A collapsible tube is indicated as at 24 60 and this tube is adapted to be removably secured to the threaded collar 23.

In operating the device the tube 24 is positioned as shown, and is squeezed or operated to cause material to pass therefrom through the aperture 22 into the body 11 and thence into the neck 12. The tube is squeezed until the material begins to pass out of the aperture 15. This indicates that the receptacle 11 is full and that the device is ready 70 for use. To use the device it is positioned by holding it in one hand, the knob 25 on the member 17 is then pressed to cause the sleeve 21 to move to close the aperture 22, and to force the contents through the opening 15. 75 When the piston 18 has been moved to its extreme position the valve member 20 will close the passage through the opening 15.

The member 17 is preferably provided with graduations 35 which indicate the capacity of 80 the chamber 36 in front of the closure 21' on the piston. By observing the graduations the amount of the preparation injected may be observed and regulated.

If desired, the piston may comprise a cup 85 as shown in Fig. 6. This cup is secured to the operating member 17 and functions in the same manner as does the construction first described.

The piston 18 has a length greater than the 90 length of its movement so that when the piston is advanced it maintains the aperture 22 closed thereby preventing the contents of the tube 24 from escaping behind the piston.

Having thus described my invention, what 95 I claim is:

1. In an applicator, a receptacle, an elongated neck projecting from said receptacle, a plunger movable in said receptacle and adapted to force material from said receptacle through said neck, a discharge opening in said neck, a valve for closing said opening, means to connect said valve and plunger for simultaneous movement and operating means on said plunger and projecting from 100 said receptacle.

2. In an applicator, a receptacle having a neck thereon, a bulbous member secured on said neck, a closure threaded to said receptacle opposite to said neck, a piston member 110 in said receptacle, a handle for operating said piston, a sleeve on said piston, an elong-

- gated rod on said piston, said bulbous member having an aperture therein and said rod having a valve member thereon for closing said aperture.
5. 3. In a measuring applicator, a receptacle having an elongated neck thereon, a bulbous member secured on said neck, a collar mounted on said receptacle and having internal threads therein, said receptacle being apertured within said collar, a closure threaded to said receptacle opposite to said neck, a piston member in said receptacle, a member for operating said piston, a sleeve in said receptacle and on said piston, said sleeve in one position allowing access to said aperture, and in another position closing access to said aperture, an elongated rod on said member, said bulbous member having an aperture

therein and said rod having a valve member thereon for closing said last mentioned aperture. 20

4. In an applicator, a receptacle having a discharge opening, an elongated plunger mounted to reciprocate in said receptacle, said receptacle having a filling aperture 25 therein, said plunger being longer than the length of its movement so that in one position it allows access to said aperture and in advanced position it closes said aperture and maintains the aperture closed, means to operate said plunger, said receptacle having a valved closure thereon and means on said plunger for controlling the valved closure. 30

In testimony whereof, I hereunto affix my signature.

ARTHUR E. SMITH.
